UNITED STATES PATENT OFFICE

2,323,068

COMPRESSOR

Pietro Maniscalco, Chicago, Ill.

Application March 29, 1941, Serial No. 385,901

16 Claims. (Cl. 230—198)

This invention relates to improvements in compressors.

One of the main objects of this invention is to provide a compressor of an economical and efficient construction, and which comprises a unitary cylinder structure including a crankcase with integral cylinders thereon, and also comprises a unitary piston structure including a body with integral pistons on its opposite ends that are reciprocable in said cylinders.

Another object of this invention is to provide a multistage compressor comprising a closed casting which includes a crankcase that serves as a lubricant chamber and has a low pressure cylinder and a smaller high pressure cylinder on its two opposite ends, all in one unitary casting or structure, wherein each cylinder has a valve head mounted on its end and carrying a readily insertable and removable valve assembly therein, for operatively closing said end.

Another object of this invention is to provide such a compressor comprising an integral piston unit which can be made economically in one casting and consists of the body having a pair of pistons integral at its opposite ends, said body being offset from the longitudinal axis thru the pistons and having channel means extending thru it for connecting chambers in the pistons; and wherein the drive means for the piston unit is arranged to operate centrally between the pistons, so as to avoid any side thrust or biased driving effect.

A further object of this invention is to provide such a compressor comprising a body having a pair of integral pistons at its opposite ends containing hollow end parts with valve assemblies therein, and including channel means extending thru said body for connecting the interiors of said end parts, thereby providing a substantially hollow body and piston ends making a light and economical construction.

Another object of this invention is to provide such a compressor which is adapted for compressing gases and refrigerants, as are used in refrigeration and air conditioning devices, and is also adapted for compressing air.

Another object of this invention is to equip such a compressor with a shut-off valve which is placed at the junction of the fluid conduit with the compressor, to prevent the loss of compressed fluid from the conduit and the connected reservoir, whenever the compressor is detached therefrom, for repairs and the like.

These and various other objects and advantages are attained with this invention, as will be

5 come apparent from the following description, taken in connection with the accompanying drawings wherein the invention is shown in its preferred form, it being evident that various other arrangements and forms of construction may be resorted to for carrying out the objects and purposes of this invention.

In the drawings:

10 Fig. 1 is a vertical sectional view, taken longitudinally thru the compressor.

Fig. 2 is a horizontal sectional view thereof, taken along line 2—2 of Fig. 1, but showing the piston unit in a different position.

15 Fig. 3 is a vertical sectional view, taken on line 3—3 of Fig. 1.

Fig. 4 is a side view of the piston unit, parts being broken away.

20 Figs. 5 and 6 are longitudinal and cross-sectional views thereof, respectively, taken on lines 5—5 and 6—6 of Fig. 4.

The present invention is disclosed herein in its preferred form of construction, being shown as a multistage compressor, which comprises a closed cylinder structure or unit including a casting 10 having a primary cylinder 11 integral on one end and a smaller secondary cylinder 12 integral on the other end, extending in opposite directions and having their longitudinal axes alined; and this compressor also comprises a 25 compact but light piston unit including a body 15 having a primary piston 16 integral at one end and a smaller secondary piston 17 integral at the other end, which are alined and reciprocable in said cylinders.

30 The cylinders 11 and 12 are open at their ends and have heads 21 and 22, respectively, mounted detachably over the openings, as by flange means 21' and 22' on said heads bolted against the cylinder ends. These heads 21 and 22 have each a 35 fluid passage therein, the two passages being shown as including chambers 23 and 24 provided, respectively, with channels 25 and 26 leading to valve devices 27 and 28 which are removably mounted on the heads 21 and 22, respectively, 40 and are connected by means of couplings or junctions 27' and 28' with inlet and outlet conduits 29 and 30, respectively.

45 Valve assemblies 31 and 32 are mounted, each removable as a unit, in the inner ends of said heads 21 and 22, respectively, between the chambers 23 and 24 and their adjoining cylinders 11 and 12, respectively, so that either assembly can be readily installed or removed. This assembly 50 31 includes a valve seat 33 and a valve element 34 urged to its closed position by a spring 35 on

the valve stem 36; while the assembly 32 includes a valve seat 37 and a valve element 38 urged to its closed position by a spring 39 on the valve stem 40.

These valve devices 27 and 28 are provided for shutting off the flow of fluid in the conduits 29 and 30, closely adjacent the heads 21 and 22, to avoid loss of fluid from the conduits and their connected containers, whenever the compressor needs to be detached therefrom, for repairs, etc. Said valve devices include a pair of tubular bodies or main portions 41 and 42 threaded to said junctions 27 and 28, respectively, and they are normally open to the connected conduits 29 and 30; while a valve stem 43 with the valve element thereon is adjustably threaded in each of said tubular bodies, adapted to be operated by turning its outer angular end 44, for closing the valve, as indicated in Fig. 2, when it is desired to shut off the conduit. A cap 45 is preferably also mounted over said outer end 44, to conceal the same.

The casing 10 supports the compressor, and being closed it serves as a chamber for housing lubricant therein, for lubricating the pistons and the drive means and the various movable elements therein.

Bypass means is preferably also provided, to take care of compressed fluid that may have leaked past the pistons into the casing, and to release any back-pressure produced due to the different sizes of the pistons. Said means comprises an escape channel 46 on the casing, and a check valve 47 connected thereto and having an element 48 depressed by a spring 49 regulated for tension by a threaded plug 50 adjustably mounted in the end of valve 47, so that this valve will open when the pressure in the casing becomes excessive. A conduit 51 connects said valve 47 with the fluid inlet chamber 23 in head 21, to return the compressed fluid thereto from the casing. A close meshed screen 47' is preferably mounted between said channel 46 and valve 47, for preventing lubricant passing with said fluid into said valve.

The piston unit herein is made of a hollow, light and easy running construction, and it with its drive means are arranged so as to prevent creating side thrust in operating the unit. It therefore has its pistons 16 and 17 made hollow at their end portions, by means of inner partition walls 52 and 53 and outer valve assemblies 54 and 55, respectively, in said end portions, thereby providing piston chambers 52' and 53' therein; while the piston body 15 is offset from the longitudinal axis of the pistons, and it contains channel means 56 therethru connecting said chambers 52' and 53'.

These valve assemblies 54 and 55 are readily installed and removed each as a unit, and they include, respectively, valve seats 58 and 59 which are threaded in the end openings in the pistons 16 and 17 and carry stems 60 and 61 having valve elements 62 and 63 slidable thereon and urged to closed position by springs 64 and 65, as illustrated. Said assemblies are shown herein in their preferred form of construction, as are also the cylinder valve assemblies 31 and 32, but they may be provided in some other approved form, mountable and removable each as a unit.

The drive means for reciprocating the piston unit comprises a shaft 67 rotatable in a pair of bearing sleeves 68 and 69 seated in a pair of collars 70 and 71 which are mounted in openings 72 and 73 provided in the opposite walls of cyl-

inder casing 10, said collars having flange means 70' and 71' thereon bolted against the casing, along with suitable sealing means therebetween as usual. Said collar 71 has a closing plug 14 threaded adjustably in its outer end, which is provided with a pocket 75 in its inner end containing therein a bearing plate 76 and a bearing ball 77 that is rotary thereon and against which the inner end 78 of the shaft 67 bears rotatably. The collar 70 has a flanged closing member 79 bolted to its outer end thru which the shaft 67 extends, and a spring 80 in the collar is confined between an enlarged part 81 on the shaft and a ball bearing including a part 82 rotary with the shaft and a part 83 seated against member 79, thus retaining the inner end of the shaft in position against ball 77.

The driving connection between the shaft and the piston unit is arranged to operate along the longitudinal axis of the unit, to avoid causing any side thrust; and in the form disclosed herein it comprises eccentric means which includes an eccentric 84 detachably fastened onto the shaft to rotate therewith, as by groove and spline means 85 provided on the eccentric and shaft, and a locking bolt 86 threaded in the eccentric to bite into the shaft. Said eccentric is rotatable in the ring portion 87 of a crank member including an arm 88 which has a pin 89 secured in its end part, as by a set screw 90; and said pin is turnable in a bore 91 provided in the piston body, and in a bore 92 provided in a lug 93 which extends inwardly from the piston 16. Lubricating ducts 94 are provided in the body and in the lug, to furnish ample passage to the lubricating means from the casing to the end parts of the pin 89.

In this construction of piston unit and drive means for the offset body, a slot 95 is provided in the body, as best shown in Fig. 4, thru which the shaft 67 extends, thus enabling the piston unit to reciprocate relative to the rotating shaft; and furthermore enabling the drive shaft to have proper bearing in the two opposite walls of the casing. The drive means including members 84 and 87 hereby also operate centrally or along the longitudinal axis of the pistons and the cylinders, so as to avoid any side thrust or biased driving effect; and these hollow pistons furthermore provide a light and economical construction.

This compressor can likewise be utilized for compressing air, as well as gases and the like, by merely detaching the inlet conduit 29 or substituting an air intake mouth therefor; and this hollow arrangement of the cylinder heads, as well as the pistons, also aids in providing a relatively cool compressor, especially when used for compressing air. The hollow integral arrangement of the cylinder structure, as well as of the piston unit, further provides an economical and light and easy running compressor.

In mounting this piston unit and the drive means in their operative positions in the cylinder structure, the valve assemblies 54 and 55 are secured in place in the pistons 16 and 17, and the drive means 87 with the pin 89 are also secured in place by the set screw 90, then the eccentric 84 may also be inserted in ring 87, instead of being entered later with the shaft 67. Said piston unit with these connected members thereon is then inserted thru the open end of the primary cylinder 11, whereupon the head 21 may be secured on the end of said cylinder; and the shaft 67 is then introduced thru the opening 72, either

with the eccentric 84 seated thereon, or is inserted thru the eccentric if that has been entered along with the piston unit, whereupon the bolt 86 is tightened by means of a tool inserted thru opening 72, thus securing the eccentric in place on the shaft and also in its ring 87. The collars 78 and 79 with their associated parts are then bolted or secured in place on the casing; and the particular driving member used, for example the pulley 98, is attached to the outer end of the shaft, and the inlet and outlet conduits 28 and 38 are operatively connected with the compressor to place it in operative condition.

I claim:

1. A compressor comprising a unitary cylinder casing and a piston unit therein, said piston unit including a slender body having a pair of integral oppositely extending pistons thereon provided each with an inner cross-wall and an outer valve member thus providing a valved end chamber and containing channel means extending thru the body and connecting said end chambers, said cylinder casing being adapted to house lubricant therein and containing integral cylinders at its opposite ends wherein the pistons reciprocate, a valved inlet head and a valved outlet head provided on the outer ends of these cylinders, a drive shaft provided with bearing means mounted in the opposite walls of the casing, for providing a closed casing, and means reciprocably connecting the shaft with the pistons and being operative in the lubricant in the casing.

2. A compressor comprising a closed and unitary casing providing a lubricant chamber and having integral cylinders at its opposite ends, valved inlet and outlet heads mounted on and closing the outer open ends of the cylinders, a piston unit including a body containing a pair of integral pistons at its opposite ends which have each a hollow end part including an integral inner partition wall and an outer valve member thereon, thereby providing a pair of valved end chambers, channel means extending thru said body and connecting said hollow end parts, and drive means including a shaft and bearing means mounting it rotary in said casing and having eccentric means thereon operable in the lubricant in the chamber, thereby providing a closed casing adapted for lubricating the contained pistons and drive means.

3. A compressor comprising a casing containing integral oppositely extending cylinders thereon provided with valved inlet and outlet means, a piston unit in said casing including a body containing a pair of integral pistons on its opposite ends having each a valved chamber at its end, said body being relatively slender and light and offset from the longitudinal axis thru the pistons, channel means extending thru said offset body and connecting said piston chambers, a slot provided in said body, a shaft and bearing means mounting it rotary in the casing to extend thru said slot and enable the piston unit to reciprocate relative to the shaft, and means in the casing operatively connecting said shaft and piston unit for reciprocating the pistons in the cylinders.

4. In a compressor including a casing having a pair of valved and aligned cylinders at its opposite ends, a piston unit comprising a unitary metal member including a pair of oppositely extending aligned pistons movable in said cylinders and having each an end chamber including an inner partition wall and an outer end opening having valve means mounted therein, also having a relatively slender and light body between

5 and integral with said pistons, the body being offset from the longitudinal axis of the pistons and having channel means extending therethru and connecting the chambers, and drive means including means operable along the piston axis for reciprocating the piston unit.

10 5. In a multistage compressor including a valved primary and a valved smaller secondary cylinder at its opposite ends and in alignment, a piston unit comprising a casting consisting of a body having integral oppositely extending primary and secondary pistons thereon which are aligned and reciprocable in said cylinders, said pistons containing each a hollow end portion 15 having an integral inner wall and an open outer end, inlet and outlet valve means operatively mounted on said open ends of the pistons thereby providing piston chambers, said body being offset from the longitudinal axis thru the pistons 20 and having channel means extending therethru for directly connecting said piston chambers, adapted to have its drive means operable along the piston axis for reciprocating the pistons.

25 6. A compressor comprising a casing having a pair of valved and aligned cylinders at its opposite ends, a piston unit including a body having a pair of oppositely extending integral and aligned pistons at its ends reciprocable in said cylinders and containing each a valved chamber in its end, the body being considerably narrower than the pistons and offset to one side of the longitudinal axis thru the pistons and having channel means extending thru it to connect said chambers, there being a slot thru the body and a lug on one of 30 the pistons, a drive shaft mounted rotary in the casing and extending thru said slot, eccentric means secured on the shaft, and means actuated by the eccentric means and including an arm with means bearing on the eccentric means and 35 also a pin on the arm connected with the lug and the body for reciprocating the piston unit without causing side thrust.

40 7. A compressor comprising a casing having a pair of valved and aligned cylinders at its opposite ends, bearing means in the side walls of the casing, a piston unit including a pair of oppositely extending aligned pistons movable in said cylinders and having each a valved chamber at its end, a piston body connecting said pistons 45 and integral therewith, being relatively slender and light and offset from their longitudinal axis and having channel means therein connecting said chambers, there being slot means provided thru said body, and drive means including a 50 shaft rotary in said bearing means and extending thru said slot means and carrying eccentric means having means thereon connected with the piston unit and operable on the piston axis, for reciprocating the pistons without causing side thrust.

60 8. A compressor comprising a closed casing adapted to contain lubricant and containing a pair of valved cylinders integral and aligned at its opposite ends, bearing means mounted in opposite side walls of the casing, a piston unit including a pair of oppositely extending aligned pistons reciprocable in said cylinders and having each a valved chamber in its end, a piston body connecting said pistons and integral therewith, being relatively slender and light and offset to one side of their longitudinal axis and having channel means therein connecting said chambers, there being a slot provided thru said body, and drive means including a shaft rotary in said bearing means and extending thru said slot, en-

abling the body to reciprocate relative to the shaft, also a pair of coengaging members one connected to the shaft and the other connected with the piston unit and operating along said piston axis within the lubricant in the casing, for reciprocating the pistons without causing side thrust thereto.

9. A compressor comprising a casing including an integral cylinder thereon having an open outer end, a piston body operable in the casing having a piston thereon reciprocable in the cylinder, a head mounted against said open end to cover it, a fluid chamber in the head and a channel extending therefrom, a check valve between the chamber and the cylinder end, a fluid conduit, and a tubular shut-off valve including flange means whereby it is mounted detachably on the head, and having a channel therein which is normally in communication with said channel and is further provided with coupling means for connection with said fluid conduit, adapted to be detached from the head and to close off said conduit whenever the compressor is to be detached therefrom.

10. A compressor comprising a casing including a pair of oppositely extending cylinders alined and integral thereon, each having an open outer end, a piston unit in said casing including a pair of oppositely extending alined pistons reciprocable in said cylinders, a head mounted against each open end to cover it and containing therein a fluid passage and a check valve between said passage and said end, a fluid conduit for each head, a shut-off valve mounted detachably on each head, being normally in communication with its passage and provided with means for connection with its fluid conduit, whereby to close off the conduits, and by-pass means with adjustable valve connecting the interiors of the casing and one of said passages, to relieve any excess pressure that may develop in the casing.

11. A multistage compressor comprising a casing closed for containing lubricant therein and including a primary and a secondary cylinder integral and alined at the opposite ends and each having an open outer end, a piston unit including a body having a primary and a secondary piston integral at its opposite ends and reciprocable in said cylinders, means movable in the lubricant in the casing for operating the piston unit, an inlet head and an outlet head mounted against and covering the open ends of said primary and secondary cylinders respectively, including each a fluid passage therein and a check valve between it and the connected cylinder end, and a shut-off valve mounted detachably on each head and including means for connecting it with a fluid conduit, whereby to close off said conduits to prevent escape of compressed fluid therefrom if the compressor needs be detached from the valves and conduits, and a valve equipped by-pass connecting the interior of the casing with the passage in the inlet head, to relieve back-pressure and excessive pressure that may develop in the casing.

12. The subject matter set forth in claim 11, wherein the pistons have valved end chambers, the body is offset from the longitudinal axis thru the pistons and is provided with channel means extending thru it and connecting said chambers, and the piston operating means is movable along said piston axis in the lubricant in the casing.

13. A multistage compressor comprising a closed casing including a larger primary and a smaller secondary cylinder alined and integral at its opposite ends, a valved inlet head detachably mounted on the end of the primary cylinder, a valved outlet head detachably mounted on the end of the secondary cylinder, a piston unit including a body having a larger primary and a smaller secondary piston alined and integral at its opposite ends and reciprocable in said cylinders, said body being relatively slender and offset from the longitudinal axis thru the pistons, and driving means including means operating along the piston axis for reciprocating the pistons, said piston unit with said operating means being insertable and removable thru said primary cylinder upon detaching said inlet head.

14. A multistage compressor comprising a closed casing including a primary and a smaller secondary cylinder alined and integral at its opposite ends and having each an open outer end, a chambered and valved inlet head detachably mounted on and covering said open inlet end of the primary cylinder, a chambered and valved outlet head detachably mounted on and covering the open end of the secondary cylinder, bearing means in the opposite casing walls, a piston unit including a body having a primary and a secondary piston alined and integral at its opposite ends reciprocable in said cylinders, said body being offset from the axis longitudinally thru the pistons and being provided with a slot transversely of it, a shaft rotary in said bearing means and extending thru said slot, and eccentric means including a member detachably attached to the shaft and a member actuated thereby and connected with the piston unit for operating it, the eccentric means being operable along the piston axis, while the piston unit with the eccentric means is insertable and withdrawable thru the open end of the primary cylinder after detachment of its head and the withdrawal of the shaft from the eccentric means.

15. The subject matter set forth in claim 14, wherein a by-pass with an adjustable check valve is provided between the interior of the casing and the chamber in the inlet head, and the inlet and the outlet head have each a shut-off valve detachably mounted thereon and interposed between its chamber and the associated fluid conduit, adapted to close said conduits when detaching them from the compressor.

16. A compressor comprising a casing having a pair of valved and alined cylinders at its opposite ends, a piston unit in said casing consisting of a metal member comprising a relatively slender and light body having a pair of integral oppositely extending pistons thereon operable in said cylinders, each of said pistons including a hollow end part containing a cross-wall in the inner end and a valve member mounted in the outer end, thereby providing a valved end chamber, said body being offset to one side of the longitudinal axis of the pistons and having channel means extending therethru connecting said chambers, and drive means including means operable along the piston axis for reciprocating the piston unit without causing side thrust.
